MACHINE FOR WINDING BALLS

Roger D. Weston and Edward L. Schick, Cuyahoga Falls, Ohio, assignors to The B. F. Goodrich Company, New York, N. Y., a corporation of New York.

Application November 29, 1947, Serial No. 788,930

18 Claims. (Cl. 242—3)

1

This invention relates to the winding of balls from a filamentary material and is especially useful in the winding of golf balls.

In the manufacture of golf balls and other play balls having a winding of vulcanized rubber thread or tape, the thread or tape is stretched substantially to its elastic limit and wound about a spherical center. Under such high tension great care must be taken to avoid abrasion of the thread or application of intermittent force there-to avoid breaking of the thread.

While it has been found possible to wind the thread by machine operation, machines heretofore designed for the purpose have of necessity been operated at relatively low speeds due to unbalance of the machine developed by movement of reciprocating parts, and while it has been proposed to provide such machines with balancing means such balancing means has not provided perfect balance at all stages of operation of the machine.

Furthermore where machines heretofore designed for their operation upon cams and followers therefor and pinions and racks which were not constantly engaged with each other, these parts have often shifted positions thereby greatly altering the desired movements when it was attempted to operate them at higher speeds thereby causing undesirable abrasion of the thread and nonuniform laying thereof.

It is an object of the present invention to overcome the foregoing and other difficulties.

Other objects are to provide good distribution of thread, to provide high speed and uniformity of operation, to provide perfect balance of the mechanism throughout the operation, to provide a ball with a true spherical winding, to reduce abrasion and breakage of the thread, and to provide increased resistance to wear of the running parts.

These and other objects will appear from the following description and the accompanying drawings.

Of the drawings,

Fig. 1a is a side elevation of apparatus constructed in accordance with and embodying the invention, parts being broken away.

Fig. 1b is a view of a portion of the opposite side thereof.

Fig. 2 is a plan view thereof, parts being broken away.

Fig. 3 is an end elevation thereof, parts being broken away.

Fig. 4 is a longitudinal vertical sectional view of the apparatus, parts being broken away.

Fig. 5 is a longitudinal horizontal sectional view taken on line 5—5 of Fig. 4.

Fig. 6 is a cross sectional view of the winding head taken on line 6—6 of Fig. 4.

Fig. 7 is a similar view, taken on line 7—7 of Fig. 4.

2

Fig. 8 is a similar view, taken on line 8—8 of Fig. 4.

Fig. 9 is a similar view, taken on line 9—9 of Fig. 4.

Fig. 10 is a similar view, taken on line 10—10 of Fig. 4.

Referring to the drawings, the numeral 10 designates a table on which a hollow box-like frame 11 is secured. The frame 11 in turn supports 10 at each end thereof a pair of spaced apart pedestal bearings 12, 13 at one end and 14, 15 at the other end, having aligned bearings for a pair of opposed spindle supporting sleeves 16, 17 movable axially toward and from each other and which 15 rotatably support opposed winding heads 18, 19 adapted to rotate in the same direction to hold and manipulate a ball center 20 during the application of a thread thereto.

The main drive shaft 25 extends longitudinally 20 of frame 11 and parallel to the axis of the sleeves 16, 17, being journaled in bearings 26, 27, 28, 29 secured to the frame 11. Near each end of the shaft 25, wide faced gears 30, 31 and 32, 33 are secured to the shaft for driving and manipulating the winding heads 18, 19, the wide faces 25 maintaining driving engagement with the gears of the winding heads while the winding heads are permitted to move axially as the ball increases in size.

30 For providing equalized movement of the winding heads toward and from each other and thereby centering the ball regardless of its growth in diameter, a pair of bell cranks 34, 35 are pivotally mounted on the frame 11, as at 36, 37 and have 35 horizontal arms having geared sectors 38, 39 at their ends meshing with each other, and forked vertical shifter arms 40, 41 engaging shifter studs 42, 43 of the sleeves 16, 17 respectively. A weight 45 is pivotally suspended from an equalizer bar 40 46 which in turn is suspended from gear sectors 38, 39 by links 47, 48. The arrangement is such that the weight 45 urges the winding heads toward each other to maintain frictional driving contact with the ball center.

45 Driving of the shaft 25 is accomplished by a motor 50 fixed to table 10 and having a pinion 51 which drives a pinion 52 running freely on shaft 25, a chain 53 transmitting motion from one pinion to the other. Pinion 52 constitutes 50 one member of a clutch, the other member 54 of which is slideably and non-rotatably mounted on shaft 25. A shifter collar 55 engages in an annular groove of the clutch member 54. A shifter fork 56 is pivotally mounted on the frame 11 and is connected to a hand operated lever 57. For quickly stopping the machine, a brake disc 58 is secured to the clutch part 54 in position to engage a fixed brake disc 59 secured to frame 11. The arrangement is such that when the lever 57 is moved to the left, it engages the clutch to drive shaft 25, and when it is moved to the right (as 55 60

seen in Fig. 1a) it applies the brake to stop the shaft 25.

The two winding heads 18, 19 are identical in mechanical construction and are driven in the same direction and operated in unison. A description of one of the heads is as follows:

The head 18 is made up of a set of annular nested members 65, 66, 67, and 68. Member 65 is formed with a hub 65a which is secured to one end of a quill shaft 69. Quill 69 is rotatably mounted in sleeve 16, ball bearings 70, 71 being provided to reduce friction. A gear-holding hub 72 is secured to the opposite end of quill 69 and removably supports a gear 73 secured thereto. Gear 73 meshes with gear 32 on the drive shaft 15 25, and is driven thereby.

A shaft 74 extends coaxially through the bore of quill 69, bearings 75, 76 therefor being provided in the ends of the quill for journaling it. A gear supporting hub 77 is fixed to the right end of shaft 74, as seen in Fig. 4, for removeably supporting a gear 78 secured thereto. Gear 78 meshes with gear 33 on shaft 25. Gears 32 and 72 have the same pitch diameter and the same number of teeth. Gear 33 is of less pitch diameter than gear 78, with the result that shaft 78 rotates at slightly less velocity than the velocity of quill 69. The arrangement is such that the head 18 is rotated at one speed while the shaft 74 extending thereinto is rotated at a slower speed to provide for manipulation of the ball center while the ball center is rotated with the head. Gears 33 and 78 are change gears and may be replaced with gears of different action when desired.

The ball center 20 is supported for frictional driving between four rollers having axes parallel to each other and parallel to the principal plane of rotation of the ball. Two of these rollers 80, 81 are mounted on winding head 18, while the other two 82, 83 are mounted on winding head 19.

It is an important object of the invention to provide for rotating the ball center discontinuously in planes other than the principal plane of rotation of the ball, or in other words the plane of rotation of the winding heads, while the winding heads are being rotated about their axes in order to distribute the thread uniformly about the center. This is accomplished by rotation of rollers 80, 81, 82, 83 all in the same direction intermittently and oscillating shifting of rollers 80, 81, 82, 83 lengthwise of their axes during rotation of winding heads 18, 19. As such shifting of rollers 80, 81, 82, 83 as heretofore has been proposed would tend to throw the winding heads 18, 19 out of balance, this invention provides for the shifting of roller 80 in one direction while the roller 81 is shifted the same amount in the opposite direction, and for a perfect balancing of all mechanism for operating the rollers at all times, thereby providing for high speed winding not heretofore attained. This is accomplished by axial movement of rollers 80, 82 in the same direction in unison and axial movement of rollers 81, 83 simultaneously in the opposite axial direction. To this end all moveable parts of the winding heads are balanced against each other and are arranged as follows:

The winding head member 68, to facilitate machining, is made in two diametrically divided segments providing therebetween a pair of guideways for slideably supporting a pair of similar U-shaped carriages 85, 86. The carriages are arranged to slide also upon rods 87, 88, 89, 90 75

supported in sockets formed in the segments. The segments also have ears 91, 92 respectively formed with bearings for rotatably supporting parallel shafts 93, 94 extending in the direction of rods 87, 88, 89, 90 and extending through clearance openings in the arms of the carriages. Rollers 80, 81 are rotatably mounted on shafts 100, 101 respectively which are fixed to the arms of carriages 85, 86 respectively. Roller 80 has a pinion 102 secured thereto which meshes with a pinion 103 slideably splined to shaft 93 and roller 81 has a pinion 104 at its opposite end which meshes with a pinion 105 slideably splined to shaft 94, the opposite arrangement of the pinions balancing these parts dynamically during their movements. Shafts 93, 94 have spiral pinions 106, 107, fixed to their opposite ends respectively for balancing reasons, and these mesh respectively with pinions 108, 109 (see Figs. 5 and 10) secured to shafts 110, 111 respectively, rotatably mounted in the winding head, with their axes parallel to the axis of rotation of the winding head and spaced radially therefrom in balanced relations to each other.

The shafts 110, 111, and with them the rollers 80, 81, are driven intermittently from shaft 74, which has fixed thereto the driving gears 115, 116 of similar Geneva stop or intermittent gear motions, the driven gears 117, 118 of which are fixed to shafts 111, 110 respectively. Each Geneva stop motion has six dwells and six rotational movements during a single revolution of shaft 74 and the dwells are made of unequal lengths so as to avoid repetition of winding axes and provide a uniform spherical winding. The gears 115 and 116 are locked together at 180 degrees to each other in rotation and are therefore balanced. As gear 78 has more teeth than gear 72, shaft 74 rotates very slowly relative to driving head 18. As the rotary movements of the rollers 80, 81 are in unequal fractional amounts the winding axis is never the same throughout the winding of the ball. Also between rotative movements, the axis of rotation is constant and not subject to displacement due to lost motion of parts regardless of speed of the machine.

For imparting axial oscillating motion to the rollers 80, 81, a pair of shafts 120, 121 are rotatably mounted in winding head members 66, 67 parallel to shaft 74 and in opposite balanced relation. Fixed to the outboard ends of the shafts are heart-shaped cams 122, 123 respectively (see Fig. 9). Cam 122 is embraced by rollers 124, 125 secured to carriage 85 and cam 123 is similarly embraced by rollers 126, 127 of carriage 86.

For driving the cams 122, 123, a gear 128 (see Fig. 8) is fixed to shaft 74. Gears 130, 131 are fixed to shafts 120, 121 respectively. A pair of stub shafts 132, 133 are secured to winder head member 66, and compound gears 134, 135 are rotatably mounted on them respectively. The compound gears have gears 136, 137 meshing with gears 138, 139 respectively and pinions 138, 139 meshing with gear 128 and fixed respectively to gears 136, 137. These gears are opposite each other diametrically of the winding head so as to balance each other. The arrangement is such that the carriages 85, 86 are oscillated constantly and the rolls 80, 81 always move in opposite directions in balance with each other and thereby rotate the ball center 20 about an axis which is always located in the winding plane but is always angularly changing its location in that plane due to rotation of the winding heads. Different combinations of gears may be provided to change the

distribution of the thread as desired. As the heart cams 122, 123 are each confined between two rollers at all times no lost motion is present at any speed. As shown in Fig. 9 these cams are faced diametrically opposite and always balance each other.

The strand of rubber thread or other material to form the winding is applied under tension and is fed from a stationary supply to the central plane of rotation of the ball. For this purpose, a bracket 150 (see Figs. 2 and 3) is mounted on the frame 11 and adjustably supports a rod 151 having a horizontal shaft 152 rotatably journaled therethrough. A sheave 153 is secured to one end of the shaft, and a brake drum 154 is secured to the opposite end. Sheave 153 is in alignment with the central plane of rotation of the ball 20. A brake strap 155 has one end anchored to bracket 150 and its other end suspends a tension weight 156. The band engages the drum 154. A second rod 157 secured to the bracket 150 adjustably supports a rod 158 having a bearing 159 for a shaft 160. Shaft 160 has a sheave 161 secured to one end thereof and a brake drum 162 secured to the other end. Sheave 161 has its axis at ninety degrees to that of sheave 153. A brake strap 163 has one end fixed to rod 157 and its other end suspends a tension weight 164. The band 163 frictionally engages the brake drum 162.

A spool supporting bracket 165 is fixed to frame 11 and pivotally supports a spool support 166 having at opposite ends spool pins 167, 168 for supporting a pair of spools, spool 169 only being illustrated. A friction lock 170 holds the spool support in the desired relation to the bracket 165.

Between the sheave 153 and the ball 20 are a pair of spaced apart guide sheaves 171, 172. The strand from sheave 153 passes under sheave 171 and over sheave 172. Sheave 172 is rotatably mounted on an arm 173 adjustably secured to a bracket 174 on the frame 11.

The strand of rubber thread passes from spool 169 under sheave 161 and over sheave 153, under sheave 171 and over sheave 172 in succession to the ball 20. Tension is applied progressively by the band brakes engaging the brake drums at sheaves 161 and 153. By the provision of a double spool holder, thread may be taken from one spool when the other is exhausted with a minimum of delay, the support being swung to position the second spool on pin 167 at the position of spool 169.

It is desirable to provide for stopping the machine should the thread break or the spool become exhausted and also to stop the machine when the balls become the desired size. For this purpose, the shifter fork 56, previously described, is secured to a rock shaft 180, on frame 11, to which a lever 181 is also secured. A bell crank lever 182 is pivotally mounted, as at 183, to frame 11. Its horizontal arm has a pin and slot connection with lever 184, as at 184, while its vertical arm is attached to one end of a tension coil spring 185. The opposite end of the spring is attached to the end of a tension adjustment bar 186, slideably mounted in a guide 187 secured to frame 11. The opposite end of the bar 186 has a longitudinal threaded opening to receive a tension screw 188 extending through a clearance aperture in frame 11. Tension of the spring 185 may be adjusted by turning the screw 188 which has a head bearing on the frame 11. The arrangement is such that the spring 185 holds

the clutch 54 released and the brake 58 engaged. A cam 189 is also secured to the rock shaft 180 for locking it in clutch-engaging position. The cam is of involute form having a stop shoulder.

- 5 A lever 190 is pivotally mounted on a stud 191 secured to frame 11. A pawl 192 is pivotally mounted on lever 190 at 193. The lever 190 normally lies in a horizontal position with the pawl 192 resting on cam 189, the free end of the lever being suspended from the armature 194 of a solenoid 195. The arrangement is such that when lever 57 (as seen in Fig. 1a) is moved to the left to engage the clutch, the pawl 192 drops on the cam 189 against its shoulder, holding the clutch in engaged position, and when the solenoid 195 is energized, it lifts lever 190 removing the pawl 192 from engagement with the shoulder of the cam whereupon spring 185 disengages the clutch.
- 10 For energizing the solenoid, to raise the lever 190, two sensitive electrical contractions are included in its circuit so that closing of either contactor will energize the solenoid. One contactor, 197, is located on the tension bracket 150. An arm 198 is pivotally mounted on rod 151 and carries a small sheave 199 at its free end. Sheave 199 rests on the tensioned thread between sheaves 171 and 172. Should the thread break, sheave 199 and arm 198 drop and contact the contactor 197 to energize the solenoid and thereby disengage the clutch, stopping the machine.
- 15 The other contactor 200 is in the path of a swinging arm 201. The arm is pivotally mounted on a cross shaft 202 extending through frame 11. A pinion 203 on cross shaft 202 meshes with a rack 204 fixed to sleeve 17. An arcuately slotted sector arm 205 is fixed to the end of the shaft and is adjustably clamped to arm 201 by a bolt 206 extending through its arcuate slot.
- 20 Arm 201 carries an adjustable stop 207 for engaging the connector 200. The arrangement is such that as sleeve 17 is moved to the left as seen in Fig. 1a, by the growth of the ball, arm 201 engages and closes the contactor 200 thereby energizing solenoid 195 and disengaging the clutch. By reason of the arcuate slot in the sector 205, the arm 201 may be adjusted to stop the machine when the ball has reached a desired diameter.
- 25 Means is also provided for manually stopping the machine at any desired time. For this purpose a cross-shaft 210 rotatably extends through frame 11 and has a hand lever 211 fixed to one end thereof and an arm 212 fixed to the other end thereof. Arm 212 extends under the free end of lever 190. The arrangement is such that when lever 211 (as seen in Fig. 1a) is moved to the right, arm 212 lifts lever 190 disengaging the clutch.
- 30 It is desirable to provide for manually separating the winding heads to facilitate placing of ball centers therebetween and for removal of finished balls therefrom. For this purpose, a bracket 215 is mounted on frame 11 and has bearings for rotatably supporting a shaft 216. A horizontal lever arm 217 is fixed to shaft 216 and extends through a clearance opening in frame 11 so that its end engages in an opening 218 in lever 38. A vertical lever arm 219 is also fixed to shaft 216. The arrangement is such that by moving arm 219 to the right as seen in Fig. 3, the sector arms 38, 39 and weight 45 are raised separating the winding heads.
- 35 In the operation of the machine, the winding heads are separated by manipulation of lever 219

and a ball center 20 is placed between the winding heads in alignment with their axis of rotation. The lever 51 is then forced to the left, as seen in Fig. 1 to disengage the brake and engage the clutch, the thread from the supply having been secured to the ball center. The winding heads rotate the ball center about their horizontal axis and also simultaneously rotate it about a rotating axis at 90 degrees thereto intermittently while also rotating it in an oscillatory manner about a moving axis at 90 degrees to the axis of intermittent motion while maintaining its center in alignment with the axis of the winding heads, thereby distributing the winding to provide a spherical ball. When the ball reaches the desired size the clutch is automatically thrown out by separation of the winding heads and the machine stops. Should the rubber thread break during winding the machine stops automatically.

The mounting of the ball engaging rollers so that two rollers always move axially in opposite directions across the face of a single winding head so as to balance each other completely, together with the arrangement of the roll-manipulating mechanism of the winding heads in continuously balanced relation, permits operation of the machine at high speeds without vibration.

Variations may be made without departing from the scope of the invention as it is defined by the following claims.

We claim:

1. Apparatus for winding a thread about a ball center to provide a spherical wound layer thereon, said apparatus comprising opposed winding heads for holding a ball center therebetween, means for rotating said heads in the same direction in unison, each head having a pair of rotatable ball centering members for contacting the ball center, and means for effecting a non-rotative movement of said centering members of a winding head in a direction transverse of the axis of rotation of said head simultaneously in opposite directions relative to said head to rotate the ball center about an axis non-coincident with the axis of rotation of the winding head.

2. Apparatus for winding a thread about a ball center to provide a spherical wound layer thereon, said apparatus comprising opposed winding heads for holding a ball center therebetween, means for rotating said heads in the same direction in unison, each head having a pair of rotatable ball centering rollers for contacting the ball center, means for effecting simultaneous rotative movement of said centering rollers of opposed winding heads to rotate the ball center about an axis normal to the axis of rotation of said winding heads, and means for effecting a nonrotative axial movement of said centering rollers of one winding head simultaneously in opposite directions relative to said head to rotate the ball center about another axis non-coincident with the axis of rotation of the winding head.

3. Apparatus for winding a thread about a ball center to provide a spherical wound layer thereon, said apparatus comprising opposed winding heads for holding a ball center therebetween, means for rotating said heads in the same direction in unison, each head having a pair of rotatable ball centering means for contacting the ball center, means for effecting simultaneous interrupted rotative movement of said centering means of opposed winding heads to rotate the ball center intermittently about an axis normal to the axis of rotation of said winding heads, and means for

5 effecting a nonrotative movement of said centering means of one winding head simultaneously in opposite directions relative to said head to rotate the ball center about another axis noncoincident with the axis of rotation of the winding head.

4. Apparatus for winding a thread about a ball center to provide a spherical wound layer thereon, said apparatus comprising opposed winding heads for holding a ball center therebetween, means for rotating said heads in the same direction in unison, each head having a pair of rotatable rollers for contacting the ball center, said rollers of each head having parallel axes spaced equally at opposite sides of the axis of rotation of said head, and means for effecting simultaneous reciprocal movement of said rollers of a driving head each along its axis in directions opposite to that of the other roller by equal amounts during the rotation of said driving head to rotate said ball center about an axis non-coincident to the axis of rotation of said winding head.

5. Apparatus for winding a thread about a ball center to provide a spherical wound layer thereon, said apparatus comprising opposed winding heads for holding a ball center therebetween, means for rotating said heads in the same direction in unison, each head having a pair of rotatable rollers for contacting the ball center, said rollers of each head having parallel axes spaced equally at opposite sides of the axis of rotation of said head, means for effecting an intermittent simultaneous rotative movement of the rollers of opposed winding heads all in the same direction during the rotation of said winding heads to rotate said ball center intermittently about an axis normal to the axis of rotation of said winding heads, and means for effecting simultaneous reciprocal movement of said rollers of a driving head each along its axis in directions opposite to movements of the other said roller on said winding head by equal amounts during the rotation of said driving head to rotate said ball center about an axis non-coincident to the axis of rotation of said winding head.

6. Apparatus for winding a thread about a ball center to provide a spherical wound layer thereon, said apparatus comprising opposed winding heads for holding a ball center therebetween, means for rotating said heads in the same direction in unison about a common axis, each head having a pair of rotatable rollers for contacting the ball center, the pairs of rollers on opposite heads having their axes parallel to each other with said rollers of each head having axes parallel and spaced equally at opposite sides of the axis of rotation of said head, said rollers of opposed heads contacting said ball center at four points of its circumference, and means for effecting simultaneous reciprocal movement of all said rollers of both driving heads in the direction of their axes with the movement of the two rollers of each winding head being at any moment in opposite axial directions and the movement of rollers of opposite winding heads having contact with the ball center at points thereof diametrically opposite each other at any moment being in opposite axial directions.

7. Apparatus for winding a thread about a ball center to provide a spherical wound layer thereon, said apparatus comprising opposed winding heads for holding a ball center therebetween, means for rotating said heads in the same direction in unison about a common axis, each winding head 75 having a pair of carriages slidably mounted there-

On for movement parallel to each other in a direction parallel to a diameter of said winding head, said carriages being equally spaced from said diameter, each carriage supporting a roller having an axis parallel to the direction of movement of the carriage for contacting a ball center, and means effecting simultaneous reciprocal movement of said carriages of a winding head in opposite directions during the rotation of said winding head.

8. Apparatus for winding a thread about a ball center to provide a spherical wound layer thereon, said apparatus comprising opposed winding heads for holding a ball center therebetween, means for rotating said heads in the same direction in unison about a common axis, each winding head having a pair of carriages slidably mounted thereon for movement parallel to each other in a direction parallel to a diameter of said winding head, said carriages being equally spaced from said diameter, each carriage supporting a roller having an axis parallel to the direction of movement of the carriage for contacting a ball center, means effecting simultaneous reciprocal movement of said carriages of a winding head in opposite directions during the rotation of said winding head, and means effecting reciprocal movement of the carriages of one winding head being connected to similar means of the opposed winding head for operation of said means of opposed heads in unison.

9. Apparatus for winding a thread about a ball center to provide a spherical wound layer thereon, said apparatus comprising opposed winding heads rotatable about a common axis, means for yieldingly urging said winding heads toward each other to retain and rotate a ball center therebetween, said winding heads each being mounted on a hollow quill shaft, means for driving both quill shafts in the same direction in unison, a pair of ball-manipulating rolls on each winding head, said rollers having their axes parallel to each other and spaced equally from the axis of rotation of said winding head in a plane of rotation perpendicular thereto, the rollers on opposed winding heads having their axes parallel to each other, each roller being mounted on a winding head for oscillating movement in a direction of its axis and for rotation about its axis, the pairs of rollers on opposed winding heads contacting the ball center at four points for holding and manipulating it, each quill shaft having a manipulating shaft rotatably extending therethrough, means for driving said manipulating shafts at a speed different from that of said quill shafts and in unison, and means on said winding heads and driven by said manipulating shafts for symmetrically oscillating rollers of a pair on each winding head in opposite directions during rotation of said winding head.

10. Apparatus for winding a thread about a ball center to provide a spherical wound layer thereon, said apparatus comprising opposed winding heads rotatable about a common axis, means for yieldingly urging said winding heads toward each other to retain and rotate a ball center therebetween, said winding heads each being mounted on a hollow quill shaft, means for driving both quill shafts in the same direction in unison, a pair of ball-manipulating rollers on each winding head, said rollers having their axes parallel to each other and spaced equally from the axis of rotation of said winding head in a plane of rotation perpendicular thereto, the rollers on opposed winding heads having their axes parallel

to each other, each roller being mounted on a winding head for oscillating movement in a direction of its axis and for rotation about its axis, the pairs of rollers on opposed winding heads contacting the ball center at four points for holding and manipulating it, each quill shaft having a manipulating shaft rotatably extending therethrough, means for driving said manipulating shafts at a speed different from that of said quill shafts and in unison, and means on said winding heads and driven by said manipulating shafts for intermittently rotating all of said rollers in the same direction during rotation of said winding heads about their axes.

11. Apparatus for winding a thread about a ball center to provide a spherical wound layer thereon, said apparatus comprising opposed winding heads rotatable about a common axis, means for yieldingly urging said winding heads toward each other to retain and rotate a ball center therebetween, said winding heads each being mounted on a hollow quill shaft, means for driving both quill shafts in the same direction in unison, a pair of ball-manipulating rollers on each winding head, said rollers having their axes parallel to each other and spaced equally from the axis of rotation of said winding head in a plane of rotation perpendicular thereto, the rollers on opposed winding heads having their axes parallel to each other, each roller being mounted on a winding head for oscillating movement in a direction of its axis and for rotation about its axis, the pairs of rollers on opposed winding heads contacting the ball center at four points for holding and manipulating it, each quill shaft having a manipulating shaft rotatably extending therethrough, means for driving said manipulating shafts at a speed different from that of said quill shafts and in unison, and means on said driving heads and driven by said manipulating shafts for intermittently rotating all of said rollers in the same direction during rotation of said winding heads about their axes, said last named means being arranged to provide consecutive dwells of different lengths of time between relative movements of said rollers.

12. Apparatus for winding a thread about a ball center to provide a spherical wound layer thereon, said apparatus comprising a rotatable winding head for supporting a ball center and rotating it to draw a thread thereunto, said winding head having ball-contacting members mounted thereon rotatable about axes equidistant from the axis of rotation of the winding head at opposite sides thereof and nonparallel thereto, means for rotating said winding head to rotate the ball center about one axis, and means for effecting an oscillating movement of said ball-contacting members bodily along their axes one in a direction opposite to the other during rotation of said winding head to rotate the ball center about an axis nonparallel to the axis of rotation of the winding head.

13. Apparatus for winding a thread about a ball center to provide a spherical wound layer thereon, said apparatus comprising a rotatable winding head for supporting a ball center and rotating it to draw a thread thereonto, said winding head having ball-contacting members mounted thereon rotatable about axes equidistant from the axis of rotation of the winding head at opposite sides thereof and nonparallel thereto, means for rotating said winding head to rotate the ball center about one axis, means for

11

effecting an oscillating movement of said ball-contacting members bodily along their axes in directions one opposite to the other during rotation of said winding head to rotate the ball center about an axis nonparallel to the axis of rotation of the winding head, and means for effecting a rotating movement of said ball contacting means during rotation of said winding head to rotate said ball center about a third axis.

14. Apparatus for winding a thread about a ball center to provide a spherical wound layer thereon, said apparatus comprising a rotatable winding head for supporting a ball center and rotating it to draw a thread thereonto, said winding head having ball-contacting members mounted thereon rotatable about axes equidistant from the axis of rotation of the winding head at opposite sides thereof and nonparallel thereto, means for rotating said winding head to rotate the ball center about one axis, means for effecting simultaneously an oscillating movement of said ball-contacting members, one in an opposite direction from the other along their axes during rotation of said winding head to rotate the ball center about an axis nonparallel to the axis of rotation of the winding head, and means for effecting a rotating movement of said ball contacting members during rotation of said winding head to rotate said ball center about a third axis, said last named means including means for effecting rotation about said third axis intermittently.

15. Apparatus for winding a thread about a ball center to provide a spherical wound layer thereon, said apparatus comprising opposed winding heads movable toward and from each other for holding a ball center therebetween, each head being mounted on a quill shaft individual thereto for rotation therewith, driving means for rotating said heads in the same direction in unison, each head having a pair of rotatable ball-centering rollers mounted thereon for contacting the ball center, each said roller being bodily movable along its axis in reciprocatory movements, each quill shaft having a spindle individual thereto extending rotatably therethrough, means for driving the spindles in unison from said driving means at a velocity different from that of said winding heads, and means carried by said winding heads and driven solely by said spindles for positively controlling the ball-centering rollers in movements relative to said winding heads both in bodily reciprocating movements of said rollers along their axes and also in rotative movement of said rollers about the axes of the rollers to rotatably manipulate the ball center about a plurality of axes for distribution of thread thereabout.

16. Apparatus for winding a thread about a ball center to provide a spherical wound layer thereon, said apparatus comprising opposed winding heads movable toward and from each other for holding a ball center therebetween, each head being mounted on a quill shaft individual thereto for rotation therewith, driving means for rotating said heads in the same direction in unison, each head having a pair of rotatable ball-centering rollers mounted thereon for contacting the ball center, each said roller being bodily movable along its axis in reciprocatory movements, each quill shaft having a spindle individual thereto extending rotatably therethrough, means for driving the spindles in unison from said driving means at a velocity different from that of said winding heads, and means carried by said winding heads and driven solely by said spindles for

12

positively controlling said ball-centering rollers both in translational reciprocating movements of said rollers relative to said winding heads in a direction axially of said rollers across the axis of rotation of said heads and also in interrupted rotative movements of said rollers about the axes of the rollers to rotatably manipulate the ball center about a plurality of axes for distribution of thread thereabout.

10 17. Apparatus for winding a thread about a ball center to provide a spherical wound layer thereon, said apparatus comprising opposed winding heads movable toward and from each other for holding a ball center therebetween, each head 15 being mounted on a quill shaft individual thereto for rotation therewith, driving means for rotating said heads in the same direction in unison, each head having a pair of rotatable ball-centering rollers mounted thereon for contacting the ball center, each quill shaft having a spindle individual thereto extending rotatably therethrough, means for driving the spindles in unison from said driving means at a velocity different from that of said winding heads, and means carried by 20 said winding heads and driven solely by said spindles for positively controlling said ball-centering rollers in translational movements relative to said winding heads comprising cam means for effecting translational movements of said members radially of said winding heads and also intermittent gear means for effecting interrupted rotative movements of said members about their axes to rotatably manipulate the ball center about a plurality of axes for distribution of thread thereabout.

35 18. Apparatus for winding a thread about a ball center to provide a spherical wound layer thereon, said apparatus comprising opposed winding heads movable toward and from each other for holding a ball center therebetween, each head being mounted on a quill shaft individual thereto for rotation therewith, driving means for rotating said heads in the same direction in unison, each head having a pair of rotatable ball-centering rollers mounted thereon for contacting the ball center, each quill shaft having a spindle individual thereto extending rotatably therethrough, means for driving the spindles in unison from said driving means at a velocity different from that of said winding heads, and means carried by said winding heads and driven solely by said spindles for positively controlling said ball-centering rollers in movements relative to said winding heads comprising cam means for effecting translational reciprocating movements of said rollers radially of said winding heads and also Geneva stop means for effecting interrupted rotative movements of said rollers about their axes and locking of said rollers between rotative movements thereof to rotatably manipulate the ball center about a plurality of axes for distribution of thread thereabout.
